EARTH MOVING DEVICE

Roy E. Choate and Waldo E. Rodler, Cedar Rapids, Iowa, assignors to La Plant-Choate Manufacturing Co. Inc., Cedar Rapids, Iowa, a corporation of Delaware

Application October 3, 1932, Serial No. 635,895

7 Claims. (Cl. 37—144)

This invention relates to earth moving devices and has particular relation to a means for absorbing shocks which affect the plow or plow manipulating mechanism of such devices.

5 We have observed that in earth moving devices where a plow, a scraper blade, or the like is movably supported with reference to the tractor or other prime mover, breakage of the supporting and actuating mechanism sometimes occurs. 10 These breakages, for the most part, upon investigation have been found to be caused, not by any normal loading of the earth moving device, but by reason of abnormal loading or sudden changes in loading such as the shock occasioned by dropping the blade or which occurs because the blade, 15 in operation, strikes a rock or other obstacle. It is possible to construct the parts of the device of heavier, stronger parts more able to meet these sudden stresses, but if this is done the machine 20 becomes unwieldy, heavy and inefficient.

After considerable investigation and experimentation we have devised a means for absorbing the shock occasioned by sudden changes in the loading and have thereby avoided the necessity 25 of providing heavy structures to meet these shocks. In a preferred form of our invention we provide a link in the plow-moving and actuating mechanism having means to permit lengthening and shortening of the link and having springs 30 for resiliently resisting such lengthening and shortening and thereby absorbing the shock occasioned by changes in loading or abnormal loading.

A general object of our invention is to provide 35 in an earth moving device a means for absorbing shocks affecting the plow and plow manipulating mechanism of such devices.

A more specific object of our invention is to provide in a plow-raising and lowering system 40 one or more resilient parts so located as to absorb shock affecting the system.

A still more specific object of our invention is to provide, in a means for raising and lowering the plow of an earth moving device, a resilient 45 link for absorbing the shock caused by sudden changes in the loading or by abnormal loading of the plow and the plow-raising and lowering means.

A feature of our invention is the provision of a 50 link of the above character which may be substituted for the usual link of such a device and in which the tension on the springs of the resilient link may be adjusted.

Another object of our invention is to provide a link of the above character which has springs

for absorbing the shock and separate guiding means so that the parts of the link are always in alignment.

Still another object of our invention is to provide a link of the above character adapted to 5 utilize multiple springs for absorbing the shock and to thereby increase the capacity of the link.

Other and further features and objects of the invention will be more apparent to those skilled in the art upon a consideration of the accompanying drawings and following specification, wherein is disclosed several exemplary embodiments of the invention, with the understanding, however, that such changes may be made therein as fall within the scope of the appended claims 15 without departing from the spirit of the invention. The device may be used or adapted for use for other purposes.

In the drawings:—

Figure 1 is a view in perspective of an earth 20 moving device in which a shock absorber mechanism constructed according to one embodiment of our invention is incorporated.

Figure 2 is a view in enlarged perspective of one link of a shock absorbing mechanism constructed according to one embodiment of our invention. This link is substantially identical with the links shown in Figure 1.

Figure 3 is a view in enlarged perspective of a 30 link constructed according to another embodiment of our invention. This link is provided with multiple springs for absorbing shock and the capacity of the link is thereby increased.

Figure 4 is a view partly in section and partly in plan of the link shown in Figures 1 and 2. 35

Figure 5 is a view in section of the link shown in Figure 4 and taken along the line 5—5 thereof.

Figure 6 is also a view in section of the link shown in Figure 4 but taken along the line 6—6 thereof. 40

Figure 7 is a plan view of the link shown in Figure 3.

Figure 8 is a view in section of the link shown in Figure 7 taken substantially along the line 8—8 thereof. 45

Figure 9 is a view in section of the link shown in Figure 7 but taken along the line 9—9 thereof.

Figure 10 is a view in perspective of one of the co-acting jaws of the body of the link shown in Figure 7. 50

Figure 11 is a diagrammatic view showing the combined hydraulic and mechanical shock absorbing system, and

Figure 12 is a view in perspective of the rear of an earth moving device in which a combined 55

hydraulic and mechanical shock absorbing system constructed according to our invention has been incorporated.

While shock absorbing links constructed according to our invention may vary widely in structure, the preferred forms here shown preferably consist essentially of three sets of parts, one set of parts including co-acting links or link portions adapted to slidably engage one another and having means for pivotally engaging the lever arms of the plow-actuating mechanism. These links are resiliently held in an intermediate or neutral position by two springs or two sets of springs, one set of which acts to bias the co-acting links apart and the other set of which acts to bias the co-acting parts of the link together. Inasmuch as the parts of the link are thus resiliently held in a neutral position, any tension or compressive stress acts to separate or move together the parts of the link and such movement is resiliently opposed by the sets of springs. The third set of parts is comprised of one or more rods upon which the springs slide and which act to hold both sets of springs in a condition of mutual initial compression.

Referring now to the drawings there is shown at 10 generally, a tractor having sub-frames 11 on the opposite sides thereof upon which wheels 12 are rotatably mounted for supporting and driving a link belt 13 for supporting and moving the tractor. Brackets 14, one on each side of the tractor, are mounted upon the sub-frames 11 and these brackets serve as bearings upon which plow-supporting frames 16 are pivotally mounted. A plow 17, which may be of any suitable or desirable construction, is attached to the front ends of the frames 16 and a pair of shoes 18 engaged upon the lower side of the front ends of the frames 16 serve to slide upon the ground and hold up the plow and the front end of the frames 16 with reference to the ground when the plow is in lowered position.

A plow-actuating means for raising and lowering the plow, such as the hydraulic jack 21, may be mounted upon the tractor in any desired position, but in the present instance the jack is pivotally mounted upon brackets 22 which are supported by a platform 23 at one side of the tractor. In the present instance a shaft 24 extends across the rear of the tractor and is mounted thereon by means of a beam 26 which engages the transmission casing of the tractor motor, or any other suitable part of the tractor and which is secured to the platform 23. Lever arms 27, one on each end of the shaft 24, project upwardly therefrom to a position adjacent and to the rear of the brackets 28 on the rear upper ends of the frames 16, and in the ordinary construction links connect the upper ends of the lever arms 27 with the brackets 28 on frames 16.

A lever arm 29 is pivotally connected to a yoke 31 on the end of the piston rod 32 of the hydraulic jack 21 and the lower end of the lever arm 29 is engaged on the shaft so that movement of the piston rod 32 causes rotation of the lever arm 29 and shaft 24 to cause a corresponding rotation of the lever arms 27 to depress or raise the rear ends of the frames 16 to correspondingly lower and raise the plow 17 at the front of the tractor. The plow actuating mechanism and the tractor construction are not the subject matter of the present invention except in connection with the shock absorbing mechanism hereinafter explained and therefore need not be further described.

75 In the embodiment of the invention shown in

Figures 1, 2, 4, 5, and 6 the link, indicated generally by the numeral 41, is comprised of a pair of inter-fitting cylinders 42 and 43, in which springs 44 and 46 and a shaft 47 are housed. The inner cylinder 42 is provided with a yoke-like extension 48 which is drilled as at 49 in order that a bolt 51 may be used for rotatably pinning this portion of the link to a lever arm such as the lever arm 27. The yoke is cored out as at 52 for lightness. If desired the opening 52 may be enlarged to such an extent that the total strength of the remaining portion of the metal of the yoke will be less than any other part of the plow actuating mechanism so that in the event of an extremely violent change in loading this yoke portion, which may readily be replaced, will break, rather than some other more expensive and less easily repairable part.

The larger outside cylinder 43 is also provided with a yoke extension 54 which is drilled as at 56 so that a pin 57 may be employed to pivotally secure the upper end of the link to the bracket 28 on the end of the beam 16. The yoke 54 is also cored out as at 58 for lightness. The size of this opening may also be so chosen that the link will break at this point under excessive or destructive loading. A partition 61 extends across the lower end of the cylinder 42 at the junction of the cylindrical portion and the yoke portion and this partition is drilled at the center so that the rod 47 may pass through the partition. A pair of diametrically-opposed slots 62 are provided in the walls of the cylindrical portion of the link 42 and a partition 63 on the inside of the larger link 43 extends through these openings and encircles the shaft 47.

In assembling the shock absorber link the shaft 47 is passed through the opening in the partition 61 and the nut 53 screwed on to the end of the shaft 47. The spring 44 is then placed on the shaft and the link 43 placed over the link 42 so that the partition 61 bears against one end of the spring 44 and the partition 63 bears against the other end. The spring 46 is then placed on the shaft 47 so that it bears against the other side of the partition 63 and the cup-like cap 64 is placed on the end of the shaft so that it bears against the other end of the spring 46. The nut 59 is then screwed on to the end of the shaft to hold the assembly in place. The link 43 is provided with a large opening 66 in order that the spring 46 may be inserted in the cylinder of the link and for lightness.

When the link 41 is in place in the plow-actuating mechanism as shown in Figure 1 it is apparent that the link 43 is normally held in an intermediate or neutral position half-way down on the link 42. It is apparent also that if tension stress is applied to the link the partition 63 will be drawn up against the compression of the spring. Obviously the pressure of the spring is compressed until the spring reaches a state of complete compression at which point no further lengthening of the link may occur.

If a compressive stress is placed on the link the partition 63 moves toward the partition 61 thus compressing the spring 44. The more the spring 44 is compressed the greater becomes the resistance to shortening of the link until the spring "bottoms" when no further shortening of the link can occur. It is obvious that the stresses of compression and tension on the link 41 are absorbed by shortening and lengthening the link against the compression of the springs 44 and 46 respectively and that any sudden change in load-

ing on the plow is absorbed by the shock absorbing link. By using a shock absorber link constructed according to our invention the effects of sudden and excessive loading on the plow are absorbed and breakage of the parts of the plow actuating mechanism is prevented. If the loading becomes too excessive one of the easily replaceable yokes of the device breaks and breakage of the more expensive parts of the mechanism is prevented. Preferably before this occurs a by-pass valve 30 (see Figures 11 and 12) in the hydraulic control system controlling the flow of fluid to, from, and in the hydraulic jack, opens to relieve the excess pressure on the jack lines and therefore the stresses on the plow actuating mechanism.

Not only do devices constructed according to our invention relieve and cushion the stresses on parts of the earth moving device under abnormal conditions, but they also cushion the parts under normal loading and thereby prolong the life of the machine.

In another embodiment of the invention shown in Figures 3 and 7 to 10 inclusive a pair of link castings 42a and 43a are employed in place of the links 42 and 43. These castings are provided with yoke members 48a and 54a which are drilled so that pins 51a and 57a may be employed for fastening the shock absorbers to the lever arm 27 and bracket 28. It is desirable that the two links 42a and 43a be slidably engaged with each other to prevent misalignment of the link while in operation and a tongue and groove arrangement for slidably engaging the two links is employed.

In the preferred embodiment of the invention a grooved lug 71 is employed on one part of the interfitting portions of the link and a pair of tongues 72 are employed on the other part of the same link. The links 42a and 43a are complementary and are cast from the same mold. It may readily be understood by reference to Figure 7 that the tongues 72 of one link fit into the grooves of the lug 71 of the other link and that the tongues of the other link fit into the corresponding grooves of the first link. The links 42a and 43a may therefore slidably engage one another and misalignment of the links with respect to one another in operation is prevented.

The link 42a is provided with cupped outwardly projecting members 76 which are provided with openings 77 therethrough. Another pair of oppositely disposed lugs 78 are also provided on the outer end of the link 42a and these lugs have openings 79 therethrough which are in line with the openings 77 in cupped members 76. The link 43a is preferably made from the same mold as the link 42a and is thus provided with cupped members 76a and lugs 78a in the same manner as link 43a. The openings 77 in the cupped members 76 and 76a and the opening 79 in the lugs 78 are sufficiently enlarged by drilling that the shafts 81 slidably engage the lugs 78, but the lugs 78a are internally threaded and the end of each shaft 81 is provided with screw threads which have threaded engagement with the lugs 78a. The shafts may be pinned by means of pins 82 which pass through the lugs 78a.

The shafts 81 extend through the lugs 76a, 76, and 78 and beyond the lugs 78 to a sufficient space that springs 46a may be located on the shafts beyond the lugs. Nuts 59a are threaded on the ends of the shafts 81 and secured in place by means of cotter pins 83. Cup-like washers 84 and 86 are disposed respectively between the springs 46a and the nuts 59a and between the

springs and the lugs 78. A second set of springs 44a are disposed on the shafts 81 between the cooperating cup-like lugs 76 and 76a.

By inspection of the drawings it becomes apparent that motion of the two halves of the 5 lengths when they are forced together is resiliently resisted by the spring 44a while any stress which tends to pull the links apart is resiliently resisted by the springs 46a. It is apparent therefore that the link indicated generally by the 10 numeral 81 and shown in Figures 3 and 7 to 10 inclusive operates in substantially the same way as link 41 hereinbefore described except that its capacity may be considerably greater because the 15 space for the springs is practically unlimited and more springs can be used.

Although we have described several embodiments of our invention it is apparent that modifications may be made by those skilled in the art. Such modifications may be made without departing from the spirit and scope of our invention as set forth in the appended claims.

We claim as our invention:

1. In a tractor, a plow disposed at the front of the tractor, frames disposed one on each side of the tractor and pivotally mounted thereon for tilting movement, and operatively engaged to the plow at the front ends thereof, a cross-shaft at the rear of the tractor, a power means for rotating the cross-shaft, a lever for connecting the cross-shaft with the power means, other levers connected to the cross-shaft and projecting to positions near the rear ends of the frames, and shock absorber links disposed between and operatively connecting the last named levers and the rear ends of the frames.

2. In a shock absorbing mechanism for earth moving devices, a pair of inter-fitting links adapted for sliding movement with respect to one another, a shaft fixed to one link and passing 40 through suitable portions of the other link, a spring disposed between the two links, and a second spring disposed between the free end of the shaft and the link through which the shaft passes.

3. In a shock absorbing mechanism for earth moving devices, a pair of inter-fitting, slidably-engaged links, a pair of shafts secured to one link and slidably engaged with the other link, one set of springs disposed on the shaft between the links, 50 and a second set of springs disposed between the free ends of the shafts and the link in which the shafts are slidably engaged.

4. In an earth moving device including a tractor, a pair of blade lifting frames mounted for pivotal movement one on each side of the tractor, actuating means for manipulating the frames comprising a rotatably mounted cross shaft at the rear of the tractor, power means for rotating the shaft, lever arms on each end of the shaft, 60 and resilient means connecting the levers with the frames for transmitting motion of the shaft to the frames and for absorbing shock between the parts of the blade actuating structure.

5. In an earth moving device including a prime 65 mover, a pair of blade lifting frames mounted one on each side of the prime mover, actuating means including levers at the rear of the tractor for manipulating the frames, and a pair of resilient links connecting the levers to the rear of the 70 frames whereby shock between the parts is absorbed.

6. In an earth moving device including a prime mover, a pair of blade lifting frames mounted for pivotal movement one on each side of the prime 75

5 mover, actuating means for manipulating the frames including levers one on each side of the prime mover at the rear thereof, and resilient means connecting the levers with the frames at the rear end of the frames for transmitting motion of the levers to the frames and for absorbing shock between the parts of the frame manipulating structure.

7. In an earth moving device including a prime
10 mover, a pair of blade lifting frames mounted

for pivotal movement one on each side of the prime mover and extending rearwardly from the pivot mounting, levers at the rear of the frames and of the prime mover operatively connected to the prime mover, and resilient means connected between the levers and the frames for absorbing shock between the levers and the frames.

ROY E. CHOATE.
